UNITED STATES PATENT OFFICE.

WILLIAM SWAIN BROWN, OF PARDOE, PENNSYLVANIA.

ENVELOP.

974,117.

Specification of Letters Patent.

Patented Nov. 1, 1910.

Application filed August 24, 1909. Serial No. 514,418.

To all whom it may concern:

Be it known that I, WILLIAM SWAIN BROWN, citizen of the United States, residing at Pardoe, in the county of Mercer and 5 State of Pennsylvania, have invented certain new and useful Improvements in Envelops, of which the following is a specification.

This invention relates to envelops, and 10 refers particularly to an improvement upon Letters Patent #869,162, granted Oct. 22, 1907.

An object of this invention is to provide a mailing receptacle which is so constructed 15 that the same may be closed without the use of an adhesive substance and will be so closed that the opening of the same will be readily detected as it necessitates the mutilation of a portion of the closure.

20 The invention has for another object the provision of a device of this character, which is simple in formation and which can be quickly and readily made from a stamped blank or form so as to produce an article 25 which is economically manufactured and may be generally used.

Further objects and advantages will appear as the description proceeds, and will be set forth in the appended claim.

30 In the drawings; Figure 1 is a perspective view of the rear side of the improved envelop in an open position; Fig. 2 is a perspective view of the front side of the same disclosing the front wall of the same as being broken away and the envelop in a closed 35 position; Fig. 3 is a central transverse section through the envelop, in a closed position.

Corresponding and like parts are referred 40 to in the following description and indicated in all the views of the accompanying drawings by the same reference characters.

Referring to the drawings 10 designates a

front wall having a tapered tongue 11 with 45 inturned flaps 12 and 13, oppositely formed at the outer end thereof to provide shoulders 14 and enlargements 20. The front wall 10 carries ends 15 and 16, and an outwardly tapered back 17 which are secured together by any suitable adhesive substance. 50 An inwardly turned locking strip 18 is integrally formed at the outer edge of the back 17 and engaged at its opposite ends between the back 10 and the ends 15 and 16. A slot 19 is formed in the upper end of the 55 back 17 to receive the tongue 11.

To close the envelop the tongue 11 is bent 60 backwardly and engaged through the slot 19. The flaps 12 and 13 now expand and engage the shoulders 14 against the lower 65 edge of the locking strip 18 to prevent the withdrawal of the tongue 11. Mutilation of the envelop is thus necessary when it is desired to gain access to the contents thereof.

Having thus described the invention, what 65 is claimed as new is;—

An envelop formed of an integral blank 70 having a front, a back, ends on the front for overlapping engagement against the inner face of the back, the end of the back 75 being turned inwardly to form a locking strip, and being held in position between the back and the ends, the back having a slot therein spaced above the lower edge of the locking strip, and a tongue formed on 75 said front and bent inwardly and diagonally to form flaps having shoulders to engage against the locking strip upon the insertion of said tongue into the slot.

In testimony whereof I affix my signature 80 in presence of two witnesses,

WILLIAM SWAIN BROWN [L. S.]
